[57] CLAIM

The ornamental design for a soap container, as shown and described.

DESCRIPTION

FIG. 1 is a first perspective view of the soap container according to the design;

FIG. 2 is a second perspective view thereof;

FIG. 3 is a top plan view thereof;

FIG. 4 is a first side elevational view thereof, the opposite side view being equal; and,

FIG. 5 is a second side elevational view thereof, the opposite side view being equal.

The container according to the design has a body that is twisted with respect to a median axis perpendicular to two opposite sides.
